UNITED STATES PATENT OFFICE.

WALTER E. SMITH, OF WINFIELD, KANSAS.

BILLIARD-CUE.

1,141,587.

Specification of Letters Patent.

Patented June 1, 1915.

Application filed August 2, 1913, Serial No. 782,716. Renewed April 22, 1915. Serial No. 23,219.

To all whom it may concern:

Be it known that I, WALTER E. SMITH, a citizen of the United States, residing at Winfield, in the county of Cowley and State of Kansas, have invented a new and useful Billiard-Cue, of which the following is a specification.

This invention relates to a pool or billiard cue and more particularly to one in which 10 the tip is detachably secured thereto.

An object of the present invention is to provide a pool or billiard cue with a quickly detachable tip.

A further object is to provide the end of a 15 billiard or pool cue with a screw extending therefrom and which is adapted to engage the tip and to rigidly secure the ferrule between the said cue and the said tip.

A further object is to provide a ferrule 20 which is adapted to slide upon and be engaged by a projection extending from the pool or billiard cue and to provide the said ferrule with a dove-tail slot extending transversely thereof and into which slot fits a 25 dove-tailed portion of a tip, there being a screw embedded in the said cue which extends through the ferrule and threadedly engages the said tip to hold the tip and ferrule rigidly in place and detachably secured to 30 the cue.

With the foregoing and other objects in view which will appear as the description proceeds, the invention resides in the combination and arrangement of parts and in the 35 details of construction hereinafter described and claimed, it being understood that changes in the precise embodiment of the invention herein disclosed, can be made within the scope of what is claimed, without 40 departing from the spirit of the invention.

In the drawings accompanying this specification the preferred form of my invention is illustrated, in which:—

Figure 1 is a view in elevation of my improved cue, showing the extreme end of the cue, the ferrule, and the tip in cross section. Fig. 2 is a similar view showing the various parts removed.

Referring to the drawings in which similar reference numerals designate corresponding parts throughout the several views, 1 is the wood or body portion of the cue and is provided with a projection 2 extending longitudinally therefrom and in which projection is embedded the screw 3.

The ferrule 4 which will usually be made

of bone or some allied substance is provided with the central bore 5 extending partially therethrough and communicating with which is the restricted or smaller aperture 6, it being noted that both the apertures 5 and 6 are formed central of the outer surface of the ferrule which is cylindrical in outline. The outer end of the ferrule 4 is provided with a dove-tail slot 7 extending transversely thereacross and which slot is adapted to detachably hold a dove-tailed portion formed upon the tip.

The tip 8 is provided with the outer rounded surface 9, the same being of the usual contour such as is adapted to contact with the balls with which the game is played. Upon the inner surface of the tip 8 is formed the dove-tailed projection 10, the same being of a size so as to slide within the dove-tail slot of the ferrule and to be securely held thereby. The tip is formed of some suitable material and is adapted to be held rigidly in place within the ferrule slot by means of the screw 3 which extends through the ferrule aperture 6 and is embedded in the said tip. As illustrated in Fig. 2 of the drawings the screw 3 is of a length sufficient to extend through the restricted aperture 6 and slightly beyond the outer extremity of the dove-tail slot of the ferrule. When it is desired to remove a tip from the cue such as I have described, the ferrule 4 is rotated to thereby also rotate the tip 8 with the result that the said tip will be retracted or unscrewed from the screw 3. When the tip has been sufficiently turned so as to be disengaged from the said screw 3, it may move longitudinally of the dove-tail slot and thereby be detached from the ferrule and may then be discarded. A new tip may then be slidably disposed within the said dove-tail slot until it comes approximately central thereof at which time the ferrule will

be rotated to thereby also rotate the said tip 100 with the result that the screw will be embedded within the tip and will wedgedly engage the same to thereby draw against the ferrule with the result that the tip and ferrule will be rigidly secured to the end of 105 the cue. With the cue as I have illustrated, the replacing and removing of the tip becomes a simple matter and it will be understood that a number of tips may be provided with each cue and as they become worn may 110 be readily discarded and new ones substituted therefor.

Having thus described the invention, what I claim to be new and original with me is:—

1. A cue comprising a body portion, a screw embedded therein and projecting therebeyond, a ferrule rotatably engaging said cue body portion and said screw, said ferrule provided with a dovetailed slot extending transversely across the outer extremity thereof, a tip with a dovetailed extension fitting within the said ferrule dovetailed slot and threadedly engaging the said screw.

2. A cue comprising a body portion with a reduced cylindrical extension projecting therefrom, a screw embedded in said extension and projecting axially therebeyond, a ferrule provided with aligned bores extending therethrough, one of said bores rotatably engaging said body portion extension, the other of said bores rotatably and slidably engaging said screw, said ferrule provided

with a dovetailed slot extending transversely thereacross and communicating with the said bores, a tip provided with a dovetailed extension fitting in and interlocking with the said ferrule dovetailed slot, said screw projecting within the dovetailed slot of the ferrule and threadedly engaging said tip, said screw drawing the tip toward the said extension and compressing the ferrule therebetween, said screw engaging the said tip substantially central thereof and forcing the sides of the dovetailed extension into wedged engagement with the sides of the dovetailed slot of the ferrule.

In testimony that I claim the foregoing as my own, I have hereto affixed my signature in the presence of two witnesses.

WALTER E. SMITH.
